UNITED STATES PATENT OFFICE

2,468,925

FLOOR ROLLER CONSTRUCTION

Herman O. De Boer, Lombard, Ill.

Application October 9, 1944, Serial No. 557,786

12 Claims. (Cl. 296—16)

1

The invention relates generally to vehicles of the type that may be used either as a hearse or an ambulance and more particularly to a floor roller construction utilized in the floor of a vehicle of this character.

The general object of the invention is to provide a novel floor roller construction in which the roller is adapted to be moved to an operative position slightly raised above the level of the floor or to an inoperative position below the level of the floor with a cover plate providing a closure for the aperture through which the roller moves, the roller being firmly supported when raised and the cover plate providing a solid portion of the floor when the roller is depressed.

Another object is to provide a novel floor roller construction which is simple in structure so that it may be inexpensively manufactured and which moves automatically from its depressed inoperative position to its raised operative position upon sliding the cover plate to its open position.

A further object is to provide a novel floor roller construction which has a total height only slightly more than the diameter of the roller so that it will not project any great distance below the top surface of the floor, and in which, when the roller is in depressed position, the cover plate lies substantially flush with the floor covering or carpeting adjacent thereto.

Still another object is to provide a novel floor roller construction in which the cover plate may be easily shifted manually between its two positions when the roller is raised or lowered, and is releasably held in such positions so that the roller is prevented from being inadvertently shifted from the desired position.

A still further object is to provide a novel floor roller construction in the form of a self-contained unit adapted to be secured in place in an aperture in the floor by means of screws applied from the top; the construction being closed at its underside and the aperture in the floor being closed, thereby to prevent access of dirt or grease from under the vehicle either to the structure of the device or to the interior of the vehicle.

Other objects of the invention will become apparent from the following description taken in connection with the accompanying drawings, in which:

Figure 1 is a perspective view of the inside of a vehicle provided with a floor roller construction embodying the features of the invention.

Fig. 2 is a plan view on an enlarged scale of the floor roller structure shown in Fig. 1.

Fig. 3 is a transverse sectional view taken on

2

the line 3—3 of Fig. 2 and showing the roller in its raised position.

Fig. 4 is a view similar to Fig. 3 but showing the roller in its depressed or lowered position.

5 Fig. 5 is a longitudinal sectional view taken on the line 5—5 of Fig. 4.

Fig. 6 is an enlarged fragmentary view similar to Fig. 2 but with parts broken away to show the interior construction.

10 It is common practice for undertakers to supply private ambulance service. In large cities where the demands for both a hearse and an ambulance are frequent, an undertaker is warranted in purchasing two vehicles, one of each kind.

15 However, in smaller communities the demand is not sufficient to warrant such an expenditure, and one vehicle is provided, which is so constructed that it may serve both purposes.

When the vehicle is used as a hearse, the floor 20 thereof is usually provided with rollers to enable the casket to be easily moved into position within the vehicle. When the vehicle is to be used as an ambulance such rollers are not used, and heretofore a false floor has been provided to cover the 25 rollers. However, the use of such a false floor reduces the head room in the vehicle, and at the time the vehicle is being used as an ambulance, a maximum head room is desired.

The present invention provides a floor roller 30 construction in which the rollers are adapted to be moved from a position below the level of the floor to a position where they project slightly above the floor, and the support for the rollers is so constructed that it lies substantially flush with the carpeting covering the floor. Thus, rollers are available when the vehicle is utilized as a hearse and when utilized as an ambulance the maximum head room is provided.

As shown in the drawings, my floor roller construction 40 comprises a body structure 10 having rectangular side walls 11 extending downwardly through an aperture 12 in the floor, the latter being indicated at 13. Extending outwardly from the upper edge of the side walls 11 is a horizontal flange 14 adapted to lie flat against the upper face of the floor and to be secured thereto as by screws 15. The flange 14 is provided with an aperture 16 located centrally of the body structure and within the area defined by the side walls 11.

45 Mounted within the body structure 10 is a roller 20 provided with trunnions 21 at each end rotatably mounted in a generally rectangular carrier frame 22. The frame 22 is pivotally mounted within the body structure so that it may swing

50 from a position where the roller 20 lies below the

flange 14 to a position where the roller projects above said flange. To this end the carrier frame 22 is pivotally supported by pins 23 extending inwardly from the ends of the body structure on an axis parallel to the roller axis and located at one side thereof. In other words, the axis of the pivot pins 23 is located within the body structure 10 and extends adjacent one edge of the carrier frame 22 so that movement of the roller 20 between its two positions is effected by a relatively small angular movement of the carrier frame 22. To provide for full support of the pivot pins 23, inwardly extending lugs 24 are formed on the rear wall 11 of the body structure to support the pins closely adjacent the ends of the carrier frame.

The carrier frame 22 is adapted to be swung automatically to its raised position by spring means comprising a pair of torsion springs 25 mounted on the pivot pins 23 and having one end abutting the rear wall of the body structure and the other end engaging a pin or boss 26 extending outwardly from the carrier frame adjacent the free edge thereof. Thus the torsion springs 25 tends to shift the roller 20 upwardly into operative position.

In order to hold the roller in its lowered position and to close the opening 16 in the top of the body structure, a cover plate 30 is provided which is slidably supported by the flange 14 of the body structure. For this purpose the flange 14 along the front side of the body structure has a depression 31 therein in which the cover plate is mounted and in which the cover plate is supported for its sliding movement. To guide the cover plate 30 in its movement, the end edges 32 (see Fig. 5) of the aperture 16 are bevelled downwardly and the cover plate is correspondingly bevelled on its edges to hold the cover plate in position in the depressed portion 31 in the flange 14. The cover plate 30 when in its closed position as illustrated in Fig. 4 overlies the roller and carrier frame and holds them in their depressed position.

The cover plate serves the further function of acting as a support for the carrier frame when the latter is in its raised position. Thus the front or free edge of the carrier frame 22 is provided with a notch 33 (see Figs. 3 and 4) adapted to seat on the edge of the cover plate when the roller is in its raised position. When the cover plate 30 is shifted from its closed position toward its open position it is first moved to the full extremity of its movement, which permits the carrier frame to automatically rise under the action of the springs 25. The cover plate 30 is then moved back a slight distance to engage the edge thereof in the notch 33. Thus the carrier frame, when the roller 20 is in operative position and adapted to carry a load, is supported both at its rear edge by the pivot pins 23 and at its front edge by the cover plate 30.

The cover plate is adapted to be limited in its opening movement so that it cannot be fully withdrawn from the depressed portion 31 of the body structure in normal operation. To this end a pair of slots 34 (see Figs. 2 and 6) are cut in the depressed portion 31 in the direction of movement of the cover plate, and countersunk screws 35 are mounted in the cover plate to engage in the slots 34 and thus limit the sliding movement of the cover plate in its opening direction.

The cover plate 30 is also adapted to be releasably retained in its closed position and in its

position for supporting the carrier frame so that it cannot be jarred out of supporting position for the carrier frame or inadvertently opened to permit the roller to rise. For this purpose the body structure is provided with a boss 36 in which is mounted a spring-pressed ball 37 adapted to engage in indentations 38 formed on the bottom face of the cover plate for its two positions. Thus the spring-pressed ball 37 will hold the cover plate against being inadvertently shifted from the desired position.

In order to prevent dirt or grease from being thrown upwardly into the body structure or through the aperture 16 into the body of the vehicle, the body structure 10 with its side walls 11 is of box-like form and is provided with a bottom wall 49 which preferably is made removable by being longitudinally slidable on the body structure. The bottom wall 49 thus may be readily removed to clean out any collection of dirt within the device. The cover plate 30 may be provided with a notch 41 adjacent its outer edge in which the finger may be inserted to facilitate movement thereof.

In a vehicle of this character, preferably a plurality of rollers are utilized. In the present instance, two rows, each consisting of five rollers, are employed. When the vehicle is to be used as a hearse, the cover plates 30 of the devices are shifted to their open positions and the rollers are automatically swung into operative position. The cover plates are then pushed slightly backwards to engage the notches 33 in the carrier frames. Thus the rollers are in operative position and are adequately supported to provide for easy movement of a casket into the body of the vehicle.

When the vehicle is to be used as an ambulance, the cover plates are shifted to their fully opened position to release the carrier frames and the rollers and frames are then pushed downwardly while the cover plate is moved toward its closed position. In this connection it will be noted that the front or free edge of the carrier frame is curved, as at 42, on an arc conforming generally to the curvature of the roller 20. Thus, by pushing the cover plate towards its closed position, the latter will effect a camming action with the curved surface 42 and the roller to force the carrier frame roller into its lowered position. When fully closed, the cover plate provides a smooth surface conforming generally to the level of the floor of the vehicle, which surface is substantially at the level of the carpeting usually placed on the floor of a vehicle of this character. Thus the floor roller shown herein provides the maximum head room within the vehicle when the latter is used as an ambulance.

The body structure 10 has a depth only slightly greater than the diameter of the roll since it need be only slightly deeper than the height of the roll and its carrier frame when the latter is in its lowered position. Thus the device does not project any material distance below the floor of the vehicle to interfere with any of the running gear thereof.

I claim:

1. A floor roller construction for use in a vehicle of the class described comprising a body structure adapted to be mounted in the floor of the vehicle, a carrier frame pivoted within said body structure, a roller mounted in said carrier frame on an axis parallel to the pivotal axis of said frame, and a cover plate slidably mounted

on said body structure and engageable with said carrier frame when in one position to hold said carrier frame and roller against movement thereof and adapted when in another position to permit the roller to project above the top of said body structure and to prevent the roller from being depressed.

2. A floor roller construction comprising a body structure having an opening in its top, a carrier frame pivotally mounted within said body structure on a horizontal axis, a roller rotatably mounted in said carrier frame, spring means tending to swing said carrier frame from a position where the roller is below the top of the body structure to a position where the roller projects above said top, and a cover plate for said opening carried by said body structure separate from said carrier frame and engageable with said carrier frame when in its closed position to hold the roller below the top of said body structure and engaging the carrier frame when in its open position to support said carrier frame with the roller projecting above the top of said body structure.

3. A floor roller construction comprising a body structure having an opening in its top, a carrier frame pivoted in said body structure on a horizontal axis, a roller mounted in said carrier frame on an axis parallel to the pivotal axis of said carrier frame, spring means coacting with said body structure and said carrier frame for urging said frame and said roller from a position below the top of said body structure to a position where the roller projects above said body structure, and a cover plate for said opening engageable with the carrier frame adjacent its pivotal axis when in its closed position to hold the roller in its lower position and with one edge of the carrier frame when in its open position to support the roller in its raised position.

4. A floor roller construction comprising a body structure having an opening in its top, a carrier frame pivoted in said body structure on a horizontal axis adjacent one edge of said carrier frame, a roller mounted in said carrier frame, spring means tending to swing said carrier frame and said roller from a position below the top of said body structure to a position where the roller projects above said body structure, and a slidable cover plate for said opening engageable with said frame when in its closed position to hold the roller in its lower position and engageable with the opposite edge of the carrier frame when in its open position to support the frame in its raised position.

5. A floor roller construction comprising a body structure having a central opening and a horizontal flange around the perimeter of said opening with a depression in said flange along one side of said opening, a roller, a carrier frame for said roller horizontally pivoted within said body structure and adapted to swing the roller from a position below said flange upwardly through said opening to project above said flange, and a cover plate slidably mounted in said depression and adapted when open to support said carrier frame along one edge thereof.

6. A floor roller construction comprising a body structure having a central opening and a horizontal flange around the perimeter of said opening with a depression in said flange along one side of said opening, a roller, a carrier frame for said roller horizontally pivoted within said body structure and adapted to swing the roller from a position below said flange upwardly through

said opening to project above said flange, a cover plate slidably mounted in said depression and adapted when open to support said carrier frame along one edge thereof, and stop means in said depression for limiting the opening movement of said cover plate.

7. A floor roller construction comprising a body structure, a carrier frame, a pair of pivots for swingably supporting said carrier frame in said body structure, said carrier frame including a roller, a pair of torsion springs mounted on said pivots and tending to swing said carrier frame from a position where the roller is below the top of the body structure to a position where the roller projects above said top, and a cover plate mounted on said body structure and engageable with said carrier frame to swing it downwardly against the action of said torsion springs.

8. A floor roller construction comprising a body structure, a carrier frame pivotally mounted in said body structure, a roller mounted in said carrier frame, spring means tending to swing said carrier frame from a position where the roller is below the top of the body structure to a position where the roller projects above said top, and a shiftable cover plate for said body structure adapted when in its closed position to hold the carrier frame in its lower position against the action of said spring means whereby movement of the cover plate to its open position permits said carrier frame to swing upwardly by the action of said spring means.

9. A floor roller construction comprising a body structure, a carrier frame pivoted in said body structure on an axis extending adjacent one edge of the carrier frame, a roller mounted in said carrier frame, spring means tending to swing said carrier frame from a position where the roller is below the top of said body structure to a position where the roller projects above said carrier frame, and a slidable cover plate for the top of said body structure, the free edge of said carrier frame being curved on an arc conforming generally to the curvature of the roller whereby said cover plate in moving toward its closed position engages said curved edge and the roller to cam the carrier frame downwardly.

10. A floor roller construction comprising a body structure, a carrier frame pivoted in said body structure, a roller mounted in said carrier frame and adapted to be shifted from a position below the top of said body structure to a position projecting above said top, a cover plate mounted on said body structure independently of said carrier frame and engageable with said carrier frame to support said carrier frame when in its open position, and a spring-pressed retainer engaging said cover plate for releasably holding said cover plate in its open and closed positions.

11. A floor roller construction comprising a box-like structure having side walls, end walls, a bottom wall, and an open top portion, said body structure being mountable in a floor opening, a roller support pivotally mounted within said body structure on a horizontal axis below said open top portion, a roller rotatably mounted in said support on an axis parallel to said first-mentioned axis, said roller support being swingable from a depressed position below said open top portion to an elevated position in which said roller and a portion of said roller support project upwardly from said body structure through said open top portion, and a retainer disposed above said body structure adjacent said open top portion and engageable with the upwardly project-

ing portion of said support for holding said roller in elevated position.

12. A floor roller construction comprising a box-like body structure having elongated side walls, end walls, a bottom wall, and an open top portion, said body structure being mountable in a floor opening, a generally rectangular carrier frame having a pair of oppositely disposed elongated sides, transverse end portions, and an elongated central opening, said frame being pivotally mounted within said body structure on a horizontal axis adjacent one of the elongated sides of said frame and adjacent one of said elongated side walls of said body structure, a roller rotatably mounted on a horizontal axis within said central opening of said frame, said frame being swingable from a depressed position below said open top portion to an elevated position in which said roller and the other of the elongated sides of said frame project upwardly from said body structure through the open top portion thereof,

and a retainer shiftably disposed above said body structure adjacent said open top portion and engageable with said other elongated side of said frame for holding said frame and roller in elevated position.
